UNITED STATES PATENT OFFICE.

DAVID E. ROSS, OF LA FAYETTE, INDIANA, ASSIGNOR TO PURDUE UNIVERSITY, OF
LA FAYETTE, INDIANA, A CORPORATION OF INDIANA.

SECTIONAL TUNNEL.

Application filed February 26, 1923. Serial No. 621,314.

This invention is a novel improvement in underground tunnels or sub-ways, particularly designed for carrying steam pipes, water pipes, electric cables or wires, and the like, which require being inspected and occasionally repaired, and its object is to provide a sectional tunnel which can be constructed economically, can be easily installed and most conveniently installed by excavating an open trench of the desired size, putting the tunnel sections therein and then filling in over the sections rather than drilling a tunnel beneath the surface; although the tunnel sections are such that they can be easily installed in place either in open trench construction or underground end to end constructions.

Another object of the invention is to so construct the sectional tunnel that the opposite side walls and top thereof can be formed of two similar opposed members which may be cast in longitudinal sections and readily assembled by simply properly positioning their bases and letting their upper ends abut, thereby forming a tunnel wall or ledge of great strength, capable of withstanding any pressure which might be imposed thereon in the ordinary use of the surface of the ground under which the tunnel extends. These tunnel sections are such that they may be formed with cheap labor, at or near the place where they are to be used, or at places quite remote therefrom, where the material for forming them may be cheaper, or more readily obtainable, and then transported to the point of use.

A further object of the invention is to provide a tunnel whose base may be formed of concrete laid within the trench or cast in slabs and placed in an excavation at any desired depth, the side and roof wall members then being readily placed upon the base, and the earth filled in over the exterior.

Other minor objects and advantages of the
45 invention will be hereinafter referred to.

In the accompanying drawings I have illustrated one practical form of the tunnel embodying the invention, and will explain the same with reference to the said drawings, 50 and summarize in the claims the essentials of the invention the novel features of construction and combination of parts for which protection is desired.

In said drawings:

Fig. 1 is a transverse section through the 55 complete tunnel embodying the invention.

Fig. 2 is an inside face view of one of the combined side wall and top section members of the tunnel.

As shown in Fig. 1, the tunnel comprises a base 1, which is preferably made of poured concrete, and is preferably continuous, but may be, if desired, laid in pre-formed sections of concrete. Preferably, after the tunnel is excavated to the proper depth, either by the open trench method, or by the boring method, the base 1 is laid by pouring concrete into suitable molds of sufficient depth to afford a firm support and anchorage for the side and roof wall members. The base should be thickened at its outer edges where the side walls are mounted upon the base, so as to withstand the wear and pressure exerted thereon by the superimposed portions of the tunnel structure. As shown, the ends of the base 1 are grooved as at 1^a to form seats or shoulders for the lower edges of the opposite side and roof wall members 2. The members 2 are also preferably formed of concrete for the purpose of economy. The contour of each section 2 is approximately one half of a parabola, or may be formed elliptical or otherwise to get additional head room. The lower portion rests upon the base 1 and extends upwardly substantially vertically for a short distance, but gradually curves inward with increasing rapidity until the upper end of the section overlies the center-line of the base 1. Thus when the two superimposed sections 2 are 25

mounted on opposite sides of the base 1 (as shown in Fig. 1) the upper edges of these sections will meet on the vertical median line or axis of the tunnel, at the top thereof, the two sections preferably forming together a complete arch, which may be either parabolic, elliptical, or conform to other mathematical curves, the parabolic form making the strongest arch section. The sections 2 are preferably composed of outer continuous sheet like portions 2^a, braced by inwardly projecting series of horizontally disposed reinforcing ribs 2^b, and vertically disposed ribs 2^c. These ribs 2^b and 2^c intersect, as shown, so that the interior surfaces of the side and roof wall members 2 present a cellular appearance, and the ribs impart the desired strength to the sections 2 while greatly re-

ducing the weight thereof. In order to give additional strength to the sections especially where the tunnel is laid under a roadway or street carrying heavy vehicular traffic, the 5 wall members 2 may be reinforced by steel rods imbedded in the body thereof in the usual manner, and further by imbedding expanded sheet metal in the web or body thereof in the usual manner.

10 Preferably each end of the wall sections terminates in a vertical rib 2^c, as shown in Fig. 2, to give strength to the abutting ends of adjacent sections. But at one end of each 15 section is also provided a flange 2^k, as shown in Fig. 2, similar to the flange of ordinary sewer pipe adapted to receive the plain end of the adjacent wall section, for the purpose of packing in the usual manner. These flanges 2^k are preferably formed integral 20 with the sections, as shown.

The lower ends of the sections are fitted in the shoulders 1^a of the base; and the upper ends of the opposed sections 2 preferably abut against opposite sides of the interposed 25 beam 3, preferably an I-beam, whose upper flanges engage respectively the abutting outer edges of the sections 2, and the lower flanges thereof fit up against the inner edges of the upper section 2, as indicated in the 30 drawings. The width between the flanges is preferably equal to the over-all thickness of the members 2. The beam serves to give true bearing for each section 2, to keep the concrete wall sections in true lineal alignment 35 along the run of the tunnel, and to prevent the edges of the sections chafing or rupturing each other by exerting unequal pressure thereagainst. From the beam 3 may be suspended by suitable hangers 4 a 40 rod 5, or track of any suitable kind, which may be used as a trolley track, or as a means for suspending blocking tackle, or by which pipes may be handled in the tunnel.

If desired, the inner faces of the members 45 2 may be covered by a lining of metal lath and plaster or any other suitable lining, as indicated in dotted lines at 6, Fig. 1, so that the cells or pockets formed by the intersecting ribs 2^b and 2^c may become closed air 50 spaces, for heat insulating purposes. Except in very cold climates it would not be necessary to thus line the tunnel.

The upper surface of the base 1 may be 55 concave as indicated in Fig. 1, so that any moisture will drain to the center of the base, and may be discharged through a suitable drain (not shown), provided in the base in the usual manner.

As stated, where the nature of the ground 60 permits, I prefer to make the tunnel by merely digging a ditch, forming the base 1 therein, then lowering the opposite sections 2 into the shoulders 1^a formed in the base 1, tilting them over until their tops abut against the interposed I-beam 3, and then

filling in the trench exterior to the sections. The joints between the adjacent sections 2 will abut, but may be closed by any suitable means in any well known manner. If desired the opposed side sections 2 may be 70 placed so that the sections on one side will stagger with the sections on the opposite side, but I do not consider this material. The construction shown affords a very cheap 75 method and means for forming tunnels, as the sections 2 can be cast in any desired size and placed bodily in position when sufficiently set, and as the sections 2 are all duplicates, one mold will answer for each and all the sections required in the straight 80 run of the tunnel.

What I claim is:

1. A tunnel of the character specified, comprising a base, opposite pre-formed combined side-wall-and-top sections semi-parabolic in shape, having their lower ends seated 85 on the opposite sides of the base and their upper ends abutting above the base, the opposed sections together forming a parabola, and a longitudinally disposed bar interposed between the upper abutting faces of opposite sections and aligning said sections.

2. A tunnel of the character specified, comprising a base, opposite pre-formed combined side-wall-and-top sections semi-parabolic in shape, having their lower ends seated 95 on the opposite sides of the base and their upper ends abutting above the base, the opposed sections together forming a 100 parabola, the sections being provided with a series of parallel longitudinal ribs and a series of vertically disposed parallel ribs on their inner faces said ribs intersecting; and bars interposed between the abutting upper 105 edges of the opposed sections, substantially as described.

3. A tunnel of the character specified comprising a base formed of concrete and having longitudinal shoulders at its sides for engagement with the side sections of the tunnel; opposite pre-formed combined side-wall-and-top sections semi-parabolic in shape, having their lower edges seated in the shoulders of the base, and their upper 110 edges abutting together at the median line of the tunnel above the base, the opposed sections together forming a parabola, and a longitudinally disposed bar interposed between the upper abutting faces of opposite 115 sections and aligning said sections.

4. A tunnel of the character specified comprising a base formed of concrete and having longitudinal shoulders at its sides for engagement with the side sections of the tunnel; opposite pre-formed combined side-wall-and-top sections semi-parabolic in shape, having their lower edges seated in the shoulders of the base, and their upper edges 120 abutting together at the median line of the 125 sections.

tunnel above the base, the opposed sections together forming a parabola; the sections being provided with series of parallel longitudinal ribs and series of vertically disposed parallel ribs on the inner faces intersecting the transversely disposed ribs; and I-beams interposed between the abutting upper edges of the opposed sections.

5. For a tunnel of the character specified, a reinforced pre-formed combined side-wall-and-top section semi-parabolic in shape and a longitudinally disposed bar interposed between the upper abutting faces of opposite sections, substantially as specified.

6. For a tunnel of the character specified, 15 a reinforced pre-formed combined side-wall-and-top section semi-parabolic in shape, the section being provided with a series of parallel longitudinal ribs and a series of vertically disposed parallel ribs on its inner face, 20 said ribs intersecting and a longitudinally disposed bar interposed between the upper abutting faces of opposite sections, substantially as specified.

In testimony that I claim the foregoing 25 as my own, I affix my signature.

DAVID E. ROSS.
